UNITED STATES PATENT OFFICE.

JACOB L. KLEINMAN, OF NEW YORK, N. Y.

TENNIS RACKET.

Application filed July 31, 1926. Serial No. 126,210.

This invention relates to tennis rackets. At the present time tennis rackets are ordinarily made with a single string comprising the playing surface of the racket and when said string is injured or broken at any one point it is necessary to remove the entire string and replace it with a new one. This takes time and is expensive. Also with the rackets at present on the market it is impossible to adjust the tension of the strings comprising the playing surface without taking the racket to an expert.

It is a primary object of the present invention to provide a racket with a playing surface having a plurality of individual strings.

It is another object to provide a racket having means to adjust the tension of each individual string.

20 A further object is to provide a racket with means whereby a string may be readily mounted and removed when necessary.

A still further object is to provide a racket having means for storing a supply of strings 25 for emergency purposes.

Other and further advantages of the invention will be apparent from the description to follow.

In the drawing, Figure 1 is a front view of a 30 tennis racket embodying my invention, a part of the handle being shown in section.

Figure 2 is an enlarged sectional view of a part of the frame of the racket showing how the bushing and its companion parts are 35 mounted therein.

Figure 3 is a bottom plan view of the bushing and its companion parts as shown in Figure 2.

Figures 4 and 5 are detail views.

40 Figure 6 is a sectional view of a part of the frame of the racket showing a modified form of the invention.

Referring to the drawing in detail, in Figure 1 is illustrated a tennis racket comprising 45 the usual frame 10 made of wood or any suitable material and oval in shape. Joined to said frame 10 in any suitable manner is a handle 11 as in the usual construction of rackets. A center piece 12 connects the sides 50 of the frame 10 together, said center piece being curved at the top for ornamental purposes.

Mounted between the sides of the frame 10 at a point just above the top of said center

piece 12 is a bridge member 13 curved to conform to the curvature of the top of said center piece 12. By reason of this construction, a space 14 is provided between the top of the center piece 12 and the lower surface of the bridge member 13 for a purpose which will be explained.

Between the sides of the frame 10 is a plurality of individual strings 15, said strings 15 being disposed longitudinally and transversely of said frame. These strings constitute the playing surface of the racket and in the ordinary construction of racket this playing surface comprises a single string. Each string 15 is mounted separately in the frame and the manner of mounting is a feature of the present invention, the strings of course being made of catgut or any suitable material.

Formed in the frame 10 at spaced points therearound and passing from its outer to its inner peripheries is a series of holes 16. Into each of said holes 16 is mounted a bushing 17 formed with an annular flange 18. The exterior of the bushing 17 is formed with serrations 19 to prevent the bushing from turning in the hole 16, and the interior of said bushing is screw threaded as indicated at 20. It will be noted from Figure 2 that when the bushing 17 is in position in the hole 16, the flange 18 rests against the outer periphery 25 of the frame 10, but it will be understood of course that this flange 18 might be embedded in said outer periphery if it is so desired. The shank portion of said bushing 17 may extend the full length of the hole 16 but in the drawing in Figure 2 it is shown as ending at a point removed from the end of the hole 16.

30 Into the bushing 17 is adapted to be mounted a string holding and tensioning device comprising a cylindrical body portion 21 provided with external screw threads 22 for a portion of its length which are adapted to engage the internal screw threads 20 of the bushing 17. The lower end of the device is closed by a base 23 but said base 23 has 35 formed in the center thereof an opening 24 to permit the string 15 to pass therethrough. It will be noted that the interior floor of said base 23 is formed with a slant as indicated at 40 25 to permit and to facilitate the ingress and egress of the string 15, no corners or sharp edges being presented to the string to stop or injure the same by reason of this construc-

tion. The upper end of the tensioning device as shown in Figure 4 is open, and formed in the periphery of said upper end at opposite points thereof is a notch 26 for the reception of a tool. The external screw threads 22 on the tensioning device and the internal screw threads 20 formed on the bushing 17 are left handed threads, and it will be noted from Figure 2 that the tensioning device has its cylindrical body 21 free from said external screw threads 22 adjacent its upper end in order to facilitate the mounting of said device in the bushing 17, the said free upper end permitting the threads to engage each other more readily as will be understood.

In use, to mount a transverse string 15, a bushing 17 is positioned in an opening 16 on the left hand side of the frame 10 for example. A string 15 of the desired length is knotted, as indicated at 27, at one end thereof, said knot 27 being of course larger than the opening 24 in the base 23. The other end of the string is passed through the open upper end of the cylindrical body 21, through the interior of said body 21 and through the opening 24 in the base 23 until the knotted end 27 rests against the slanting floor of said base. The cylindrical body 21 is then mounted in the bushing 17 by inserting its free upper end into the hole 16 on the periphery on the inside of the frame 10 and turning it to the right so that the threads 20 and 22 engage each other, and said threads being left handed the said tensioning device will move longitudinally of said bushing in the direction of the end forming the flange 18. The free end or the unknotted end of the string 15 is then drawn over and under the adjacent longitudinal strings 15 until it has passed the last longitudinal string 15 on the opposite side of the frame 10, when the said free end of the string 15 is then passed through the opening 24 in the base 23 of a second tensioning device and knotted, the cylindrical body portion 21 of which is then screwed into another bushing 17 mounted in the hole 16 at a point directly opposite said first hole 16. By turning this second tensioning device to the right, it will be drawn longitudinally of the second bushing 17 in the direction of the outer periphery of the frame 10, and while thus moving in this direction it will be drawing the string 15 along with it, taking up the slack and making the said string taut. While rotating within the bushing 17, the tensioning device twists the string 15 thereby tightening the weaves of said string, which results in strengthening the said string. It will be understood of course that in order to adjust the tension, that is slacken or tighten a string, all that it is necessary to do is to turn one of the tensioning devices to the left or right. To remove a string 15 all that it is necessary to do is to turn the tensioning devices to the left

and they will move out of position in the bushing 17 when the string may be readily removed.

A longitudinal string 15 is mounted and removed and tensioned in the same manner.

In case of emergency it is often wise to have a supply of strings 15 on hand so that the racket may be repaired. It is a feature of this invention to provide means for storing such a supply. This is accomplished by boring a central chamber 28 in the outer end of the handle 10 into which a supply of string 15 may be placed. Into this chamber 28 at its outer end is mounted a sleeve 29 formed with a collar 30 adapted to rest when in operative position on a shoulder 31 formed in the chamber, said sleeve 29 being internally screw threaded. Mounted in the sleeve 29 and adapted to seal up the opening in the chamber is a tool 32 shown in the drawing as a screw driver having a shank portion, a knurled knob 33, and an externally screw threaded portion adapted to engage the internal screw threads on the sleeve 29. This tool may be used for turning the tensioning devices by inserting its shank into the flanged end of the bushing 17 and into the notches 26 on the cylindrical body 21, the said shank being only as wide as the said cylindrical body 21 at its notched end, thereby eliminating any chance of said tool injuring the internal threads 20 formed on said bushing.

In the modified form of the invention illustrated in Figure 6, a series of openings 34 are formed at spaced points in the face portion of the frame 10, that is, formed at right angles to the openings 16 shown in the other form of the invention, and concentric with said opening 34 is another opening 35 larger in diameter and extending to the surface of the frame, the latter opening 35 being as deep as desired but illustrated in Figure 6 as being very shallow. Into this opening 35 is mounted a sleeve 36, said sleeve 36 being octagonal or hexagonal in shape to prevent the same from turning in the opening 35. Mounted in the opening 35 is a pin 37 formed with an elongated shank and a head 38 shaped like the sleeve 36 and adapted to be inserted into said sleeve 36. Passing through the shank portion of the pin 37 at about its center is an opening 39. In using this form of the invention, a hole 40 is formed in the inner periphery of the frame 10 at right angles to the opening 34, and the string 15 is passed therethrough and through the said opening 34 in the shank of the pin 37 when the said pin is in operative position as shown in Figure 6. In order to tighten the said string 15, it is necessary to draw the head 38 of the pin outwardly away from the sleeve 36 and when it is free of said sleeve the pin may be turned, turning with it the string 15 and thereby tightening the same. When the string is sufficiently taut, the head 38 is

pushed back into the sleeve 36 and the parts are held against further turning.

While I have described several embodiments of my invention, it will be understood that many minor changes may be made in the construction and arrangement of parts and I desire to be limited only by the state of the art and the appended claims.

I claim:

- 10 1. A racket comprising a frame, a handle therefor, said frame formed with a plurality of openings around its periphery, a bushing mounted in each of said openings, a plurality of strings stretched between said frame, and a device for tensioning and twisting each of said strings mounted in each of said bushings.
- 15 2. A racket comprising a frame, a handle, a string tensioning device mounted in said frame, and removable means forming a part of said handle for operating said tensioning device.
- 20 3. A racket comprising a frame, a handle, a tensioning device mounted in said frame, and a removable turning tool forming a part of said handle for operating said tensioning device.
- 25 4. In a racket, a frame, a handle, a tensioning device mounted in said frame, and a removable turning tool forming a part of said handle for operating said tensioning device.

of said openings, a plurality of strings stretched between said frame, and a device for tensioning and twisting each of said strings mounted in each of said bushings.

30

3. A racket comprising a frame, a handle therefor, a plurality of individual strings stretched therebetween, a plurality of rotatable devices for tensioning said strings mounted in said frame, means for operating 35 said tensioning devices, means within said frame for storing a supply of said strings, said operating means forming a part of said last mentioned means when not operating said tensioning devices.

40

4. In a racket, a frame, a handle, a string tensioning device mounted in said frame, and removable means forming a part of said handle for operating said tensioning device.

45

5. In a racket, a frame, a handle, a tensioning device mounted in said frame, and a removable turning tool forming a part of said handle for operating said tensioning device.

In testimony whereof I hereunto affix my signature.

JACOB L. KLEINMAN.
